INTAKE MUFFLER

Wilfrid E. Johnson, Schenectady, N. Y., assignor
to General Electric Company, a corporation of
New York

Application February 1, 1936, Serial No. 61,947

6 Claims. (Cl. 181—47)

My invention relates to intake mufflers for refrigerant compressors or other machines in which successive quantities of an elastic fluid are supplied to the machine.

In refrigerant compressors of the reciprocating type, for example, successive quantities of gaseous refrigerant are supplied through a suitable intake valve mechanism to the compressor cylinder during the successive intake strokes of the piston. It is desirable in designing such a machine to provide some arrangement for minimizing or substantially preventing the transmission of sound waves through the entering fluid, caused by the operation of the compressor valve mechanism or the like, in order to minimize the noise of operation of the machine. This problem is especially important in machines designed for household use since particular care should be taken to make their operation as unobtrusive as possible from the standpoint of noise.

It is an object of my invention to provide an improved intake muffler for a refrigerant compressor or the like in which sound waves set up in the fluid supplied to the compressor are confined within a closed muffling chamber. I accomplish this by providing an arrangement at the inlet of the muffling chamber restricting the effective area of the inlet for maintaining the velocity of the fluid flowing therethrough, during the normal operation of the machine, at a value greater than the acoustical velocity of the fluid. As a consequence the egress from the inlet of sound waves set up in the fluid by the operation of the compressor valve mechanism or the like is substantially prevented.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a side elevation, partly in section, of a refrigerating machine provided with an intake muffler embodying my invention, and Fig. 2 is an enlarged plan view partly in section, of the intake muffler shown in Fig. 1.

Referring to the drawing, I have shown in Fig. 1 a compression type refrigerating machine especially designed for household use, which includes a Scotch yoke type refrigerant compressor 10 mounted on the top of and driven by a vertical electric driving motor 11. The com-

pressor 10 and driving motor 11 are mounted within a cylindrical hermetically sealed steel casing 13 on a series of vertical helical compression springs 14. Gaseous refrigerant, such as dichlorodifluoromethane (CCl_2F_2) is supplied from the interior of the casing 13 to the compressor 10 through an intake muffler 15, embodying my invention. The gaseous refrigerant compressed in the compressor 10 is discharged therefrom through a discharge conduit 16 and flows through to a discharge muffler 17. The compressed gaseous refrigerant then flows from the discharge muffler 17 through a conduit 18 to an elongated refrigerant circulatory passage 19 of a sheet metal cylindrical natural draft air-cooled condenser 20. The condenser 20 surrounds the casing 13 and is mounted on a series of radial heat conducting fins 21 interposed between the adjacent surfaces of the casing and condenser 20. Refrigerant vapor flowing through the refrigerant circulatory passage 19 is cooled by the transfer of heat therefrom to the surrounding air which flows upwardly over the surfaces of the condenser 20 and between the casing 13 and condenser 20 over the surfaces of the fins 21 due to natural draft. The refrigerant thus liquefied in the condenser 20 flows therefrom through a conduit 22 to a flow controlling float valve 23 from which it is supplied through a liquid line 24 to an evaporator 25.

The evaporator 25 is supported on the lower side of a removable heat insulated top wall 12 of a refrigerator cabinet and within a cooling compartment of the refrigerator, which the evaporator is adapted to cool. The liquid refrigerant within the evaporator 25 is vaporized by the absorption of heat from the compartment in which it is located and the vaporized refrigerant is collected in a longitudinal cylindrical header 26 above the level of the liquid refrigerant therein. The header 26 is normally maintained about half full of liquid refrigerant so that the remainder of the evaporator 25 is flooded with liquid refrigerant. The vaporized refrigerant thus collected in the header 26 passes therefrom through a conduit 27 to the interior of the casing 13. The vaporized refrigerant within the casing 13 is again supplied to the compressor 10 through the intake muffler 15 and the cycle described above is repeated and continued until the compartment in which the evaporator 25 is located is cooled to the desired temperature.

The intake muffler 15 includes a tubular metal casing 28, which may conveniently be formed

from a section of ordinary seamless tubing. The casing 28 is preferably arcuate in shape in order that it may be secured to the top of the electric driving motor 11 and extend about the rear end 5 of the compressor 10 thus forming a compact arrangement of the parts of the compressor unit mounted within the hermetically sealed casing 13. The ends of the casing 28 are closed by cup-shaped sheet metal caps 29 and 30 which are 10 brazed or otherwise hermetically sealed thereto. Holes 31 and 32 are formed in the flanged portions of the caps 29 and 30, respectively, and these holes register with similar holes formed in the end portions of the casing 28. Suitable bolts 15 33 and 34 passing through the holes 31 and 32 respectively, as well as the registering holes in the casing 28 secure the casing in position on top of the driving motor 11 and also aid in holding the caps 29 and 30 in position within the 20 ends of the casing 28. A flanged outlet opening 35 is formed in the cap 29 and one end of a conduit 36 is brazed or otherwise hermetically sealed to the sides thereof. The conduit 36 conveys vaporized refrigerant from the interior of the 25 fluid muffling chamber 37 formed by the casing 28 to the inlet of the compressor 10. A flanged inlet opening 38 is formed in the cap 30 at the opposite end of the fluid muffling chamber 37.

I have provided an arrangement restricting the 30 effective cross-sectional area of the inlet opening for maintaining the velocity of the vaporized refrigerant or vaporized refrigerant flowing therethrough, during the normal operation of the compressor, at a value greater than the acoustical 35 velocity of the vaporized refrigerant to thereby substantially prevent the egress from the inlet of sound waves set up in the vaporized refrigerant within the muffling chamber 37 by the operation of the compressor valve mechanism and the like. As best shown in Fig. 2, this arrangement 40 includes a tubular nozzle 39 which is mounted in the flanged inlet opening 38 and is brazed or otherwise hermetically secured to the walls thereof. The nozzle 39 is provided with a sharply 45 flared inlet passage 40 which communicates with a relatively narrow restricted throat 41. The nozzle is also provided with an elongated outwardly flaring discharge passage 42 which communicates with the throat 41. Although vaporized refrigerant is drawn into the compressor 10 50 in successive quantities upon each suction stroke of the compressor piston, the volume of the muffling chamber 37 is made large as compared to the displacement of the compressor, so that the pulsations of pressure within the chamber 37 will be relatively small. In the machine illustrated the volume of the muffling chamber 37 is approximately twelve times the displacement of the compressor. As a consequence, the vaporized refrigerant flowing through the nozzle 39 55 into the muffling chamber 37 moves at a velocity which is relatively constant. The cross-sectional area of the throat 41 of the nozzle 39 is so proportioned with respect to the average flow of vaporized refrigerant required by the compressor 60 that the velocity of flow of vaporized refrigerant through the throat 41 will be equal to or greater than the acoustical velocity of the vaporized refrigerant. The acoustical velocity, or rate 65 of travel of sound waves through any gas, may be expressed by the well known equation:

$$v = \sqrt{\frac{\gamma P}{d}}$$

70 where v is the acoustical velocity of the gas in

ft. per second, P is the absolute pressure of the gas in lb. per sq. ft., d is the density in lb. mass per cu. ft., and γ is the ratio of specific heats of the gas at constant pressure and volume, respectively. From an inspection of this equation, it will be apparent that the acoustical velocities for different gases may vary widely. Thus, the acoustical velocity for air at 50 deg. F. is approximately 1100 ft. per second, while that for sulphur dioxide is approximately 800 ft. per second and that for dichlorodifluoromethane is approximately 500 ft. per second. Consequently, the dimensions of the throat 41 of the nozzle 39 must also be proportioned in view of the particular gas to be used in the machine. I prefer to use dichlorodifluoromethane as the refrigerant for the machine because it has a low acoustical velocity so that the throat 41 of the nozzle 39 may be made less restricted and hence the losses caused thereby minimized. The discharge passage 42 of the nozzle 39 diverges or flares gradually so that the velocity head of the vaporized refrigerant flowing through the nozzle may be reconverted to pressure head without substantial loss.

It will be seen that in such an arrangement as 2 that described above that any sound waves set up in the vaporized refrigerant in the muffling chamber 37 by the operation of the valve mechanism of the compressor or the like will be confined within the muffling chamber 37 since they 3 cannot pass through the throat 41, as the vaporized refrigerant flowing therethrough is moving inwardly at a velocity equal to or greater than the velocity of the sound waves. Thus no sound waves can be transmitted from the vaporized refrigerant within the muffling chamber 37 through the vaporized refrigerant within the casing 13 to the walls of the casing and the noise of operation of the machine is, consequently, minimized. It should also be noted that no 40 pulsations in flow of vaporized refrigerant through the nozzle 39 will result from any pulsations in pressure within the muffling chamber 37, so long as the pressure within the hermetically sealed casing 13 is maintained at a substantially 45 constant value. This arises from the fact that when the nozzle 39 is designed to accommodate the average flow of vaporized refrigerant therethrough required by the compressor, then no matter what the reduction of pressure within the 50 muffling chamber 37 no greater flow through the nozzle 39 than the predetermined average can be obtained. Thus, no matter how the pressure pulsates within the muffling chamber 37 no pulsations can occur outside the nozzle 39. In this respect, it is desirable to make the volume of the muffling chamber comparatively large in order to prevent excessive pulsations in pressure therein and consequent loss in efficiency.

While I have shown a particular embodiment 60 of my invention in connection with a compression type refrigerating machine designed for household use, I do not desire my invention to be limited to the particular construction shown and described, and I intend in the appended 65 claims to cover all modifications within the spirit and scope of my invention.

What I claim as new and desire to secure by Letters Patent of the United States is:

1. An intake muffler for a refrigerant compressor or the like comprising a chamber having a relatively large volume as compared to the displacement of the compressor used therewith, said chamber having an inlet and an outlet, and means restricting the effective cross-sec- 75

5   tional area of said inlet for maintaining the velocity of the fluid flowing therethrough during the normal operation of the compressor at a value greater than the acoustical velocity of the fluid to thereby substantially prevent the egress from said inlet of sound waves set up in the fluid by the operation of the compressor.

2. An intake muffler for a refrigerant compressor or the like comprising a chamber having 10 a relatively large volume as compared to the displacement of the compressor used therewith, said chamber having an inlet and an outlet, and means in said inlet including a nozzle having a throat of relatively restricted cross-sectional area 15 for maintaining the velocity of the fluid flowing therethrough during the normal operation of the compressor at a value greater than the acoustical velocity of the fluid to thereby substantially prevent the egress from said inlet of sound waves set 20 up in the fluid by the operation of the compressor.

3. An intake muffler for a refrigerant compressor or the like comprising a chamber having a relatively large volume as compared to the displacement of the compressor used therewith, 25 said chamber having an inlet and an outlet, and means including a nozzle located at said inlet for maintaining the velocity of the fluid flowing therethrough during the normal operation of the compressor at a value greater than the acoustical 30 velocity of the fluid to thereby substantially prevent the egress from said inlet of sound waves set up in the fluid by the operation of the compressor, said nozzle having a throat of relatively restricted cross-sectional area and an elongated 35 outwardly flaring discharge passage communicating with said throat.

4. An intake muffler for a refrigerant compressor or the like comprising a tubular casing having a relatively large volume as compared to 40 the displacement of the compressor used therewith, means including caps extending across the opposite ends of said casing and hermetically secured thereto for closing the same, one of said caps having an outlet opening formed therein and the other of said caps having an inlet opening formed therein, and means restricting the effective cross-sectional area of said inlet for maintaining the velocity of the fluid flowing there- 45

through during the normal operation of the compressor at a value greater than the acoustical velocity of the fluid to thereby substantially prevent the egress from said inlet of sound waves set up in the fluid by the operation of the compressor. 5

5. An intake muffler for a refrigerant compressor or the like comprising a tubular casing having a relatively large volume as compared to the displacement of the compressor used therewith, 10 means including caps extending across the opposite ends of said casing and hermetically secured thereto for closing the same, one of said caps having an outlet opening formed therein and the other of said caps having an inlet opening formed therein, and means including a nozzle positioned in said inlet opening and having a throat of relatively restricted cross-sectional area 15 for maintaining the velocity of the fluid flowing therethrough during the normal operation of the compressor at a value greater than the acoustical velocity of the fluid to thereby substantially prevent the egress from said inlet of sound waves set 20 up in the fluid by the operation of the compressor. 25

6. An intake muffler for a refrigerant compressor or the like comprising a tubular casing having a relatively large volume as compared to the displacement of the compressor used therewith, 30 means including cup-shaped sheet metal caps positioned in the ends of said casing and hermetically secured thereto for closing the same, one of said caps having an outlet opening formed therein and the other of said caps having an inlet opening formed therein, means including a nozzle positioned in said inlet opening for maintaining the velocity of fluid flowing therethrough during the normal operation of the compressor at a value greater than the acoustical velocity of 35 the fluid to thereby substantially prevent the egress from said inlet of sound waves set up in the fluid by the operation of the compressor, said nozzle having a throat of relatively restricted cross-sectional area and an elongated outwardly 40 flaring discharge passage communicating with said throat. 45
